UNITED STATES PATENT OFFICE.

JESSE T. SHEETS, OF COVINGTON, KENTUCKY.

MEANS FOR SUPPORTING STRETCHERS IN AMBULANCES.

986,650.

Specification of Letters Patent. Patented Mar. 14, 1911.

Application filed October 1, 1909. Serial No. 520,490.

To all whom it may concern:

Be it known that I, JESSE T. SHEETS, a citizen of the United States of America, and resident of Covington, Kenton county, State 5 of Kentucky, have invented certain new and useful Improvements in Means for Supporting Stretchers in Ambulances, of which the following is a specification.

The object of my invention is a means of 10 swinging or supporting a stretcher in the ordinary patrol wagon or ambulance, by which the injured person is carried with greater comfort to himself, a physician or surgeon is enabled to work with him with 15 greater ease, and others who have sustained minor injuries may also be conveniently carried in the wagon at the same time.

In the accompanying drawing, Figure 1 is a rear elevation of a patrol wagon, showing 20 the stretcher embodying my invention in position. Fig. 2 is a plan view of the patrol wagon, with the roof removed and showing the stretcher in position, with portions of the cloth cut away to show the brackets. Fig. 3 is a central sectional view 25 of the spring cylinder or dash pot. Fig. 4 is a detail view, upon a large scale, of the bracket which supports the stretcher. Fig. 5 is a perspective view, showing the bracket 30 and spring cylinder in place and the bracket swung parallel to the seat to facilitate the convenient handling of the stretcher. Fig. 6 is a perspective view showing the bracket and spring cylinder in place and the bracket 35 swung into position for the reception of the stretcher.

Referring to the parts, by letters: (A) is the spring cylinder and (B) is the bracket upon which the stretcher (C) is supported. 40 The spring cylinder is fastened in some convenient manner to the side of the seat (F). The body of the spring cylinder (A) has heads (a) (a), which are screwed into place. Within this cylinder are the cups (a¹) (a²) 45 (a³), which act as guides for the springs (a⁴) and (a⁵). The cup (a²) is held in position by means of a lock nut (a⁶) and a coupling (a⁷), which also unites the two rods (a⁸) and (a⁹). The rod (a⁹) extends 50 through the bottom head (a) and the floor of the vehicle and by this means affords greater support to the bracket (B) and

stretcher (C). The rod (a⁸) extends through the top head (a), and over this is slipped the hollow support (b) of the 55 bracket (B). The bracket (B) is provided with two arms (b¹) and (b²), which are forked at their outer ends (b³) and (b⁴). These forks form receptacles for the rods of the stretcher. 60

The operation of the device is as follows: The patient is placed on the stretcher and the brackets are placed in a position parallel with the seat. The stretcher is then carried into the patrol and the brackets are 65 swung into position to receive the rods of the stretcher. The spring (a⁵) prevents the jarring of the vehicle from disturbing the patient. Spring (a⁴) takes up any reaction of spring (a⁵), thus rendering the 70 movement of the stretcher more even. When not in use brackets, B, are lifted off of rods (a⁸).

I do not desire to be confined to the exact details shown, but aim in my claims to cover 75 all modifications which do not involve a departure from the spirit and scope of my invention.

What I claim is:

1. In an ambulance having side seats, the 80 combination of stretcher supporting brackets, each bracket being provided with arms for engaging both sides of the stretcher, and means located adjacent to one of the seats of the ambulance and below said arms for 85 yieldingly supporting said brackets.

2. In an ambulance having side seats, the combination of stretcher supporting brackets each bracket being provided with arms for engaging both sides of a stretcher, and 90 means adjacent to one of the seats of the ambulance for yieldingly supporting each bracket, so that one arm of each bracket projects over the adjacent seat.

3. In an ambulance having a longitudinal seat, cylinders mounted adjacent to said seat, a vertically extending rod yieldingly mounted in each cylinder, and a stretcher supporting bracket, provided with divergent arms for engaging both sides of a 95 stretcher, rotatively mounted on each rod.

4. A stretcher supporting bracket comprising upwardly extending divergent arms, for supporting each side of a stretcher, and

a downwardly extending support secured thereto, in combination with a cylinder located below said bracket, a vertical rod extending into said cylinder, means secured to said rod to guide it along said cylinder and for supporting said bracket, a coiled spring for supporting said rod located within said

cylinder below said means and a recoil spring located within said cylinder above said means.

JESSE T. SHEETS.
